Design U.S. Appl. No. 29/528,169, filed May 27, 2015.

Primary Examiner — Robert M Spear*Assistant Examiner* — Darcey E Heflin(74) *Attorney, Agent, or Firm* — McLane Middleton, Professional Association(57) **CLAIM**

The ornamental design for a tip for dispenser pump, as shown and described.

DESCRIPTION

FIG. 1 is a perspective view of a tip for dispenser pump, taken generally from the top and right side, showing the new design;

FIG. 2 is a perspective view thereof, taken generally from the bottom and right side;

FIG. 3 is a perspective view thereof, taken generally from the bottom and rear side;

FIG. 4 is a top plan view thereof;

FIG. 5 is a bottom plan view thereof;

FIG. 6 is a right side elevational view thereof, the left side elevational view being identical thereto; and,

FIG. 7 is a front elevational view thereof, the rear elevational view being identical thereto.

The broken lines in the drawings illustrate features that form no part of the claimed design.
